UNITED STATES PATENT OFFICE

2,495,910

SINGLE-EDGE RAZOR BLADE
SHARPENER

William W. Syfert, Oklahoma City, Okla.

Application September 5, 1947, Serial No. 772,257

1 Claim. (Cl. 51—98)

1

This invention relates to a sharpening mechanism for sharpening single edge razor blades.

An object of the invention is to provide a housing having mounted therein a rotary sharpening or honing means, which is especially adapted to sharpen or hone single edge razor blades.

A razor blade becomes dull and scratchy—many with a single shave. The dullness is occasioned by the wearing away of the cutting edge. If the cutting edge is nicked, bent or flattened, the razor becomes scratchy. However, the wear on the cutting edge is not always discernible to the naked eye.

Another object of the invention, therefore, is to provide on the rotary sharpening means, or honing means, a plurality of sharpening elements which are made of leather or a composition leather, and mounting these elements in a zig-zag manner so that the blade will receive the same type of honing or sharpening effect as would be obtained by drawing a scythe stone over the cutting edge of a scythe.

With the above and other objects and advantages in view, the invention consists of the novel details of construction, arrangement and combination of parts more fully hereinafter described, claimed and illustrated in the accompanying drawing in which:

Figure 1 is an elevational view of an embodiment of the invention;

Figure 2 is a side elevational view of Figure 1;

Figure 3 is a vertical sectional view on the line 3—3 of Figure 1;

Figure 4 is a transverse sectional view on the line 4—4 of Figure 1;

Figure 5 is a detailed sectional view on the line 5—5 of Figure 1;

Figure 6 is an enlarged detailed sectional view on the line 6—6 of Figure 2 and

Figure 7 is an elevational view of the sharpening and honing means.

Referring more in detail to the drawing, the sharpener embodying the invention is generally designated by the reference numeral 10. The sharpener comprises a dome-shaped hollow casing 11, having a base 12, which is countersunk at 13 to receive the removable bottom plate 14 of the housing.

Extending transversely of the housing is a square shaped shaft 15, having the rounded ends 16 journalled in bearings 17 which are removably mounted in the countersink 18 in the opposite sides of the casing 11. A washer 19 is removably secured to one end of the shaft 15 by the screw 20, while a crank 21 is removably secured to the

2

opposite end by a screw 22. Fixed to the shaft 15, inwardly of the crank 21, is a ratchet disc 23 which is engaged by the dog 24 mounted at 25 on the casing 11, so that the shaft can be turned clockwise by means of the crank 21, but cannot be turned anti-clockwise.

Removably mounted on the shaft 15, by means of the centrally located square-shaped base 26, is the wooden roller 27 on the periphery of which, is formed the zig-zag countersink 28, in which is suitably secured the zig-zag strip of sharpening and honing material 29 which is made of leather or a suitable substitute therefor. The thickness of the material 29 permits it to be slightly raised beyond the peripheral surface of the roller 27. The formation of the material 29 gives a sharpening and honing effect similar to the effect caused by drawing a stone over the sharpened edge of a scythe.

Secured to the sides of the casing by rivets 30, at positions slightly below the summit of the dome-shaped housing 11, are the L-shaped brackets 31.

A plate 32 is secured to the brackets 31 by screws 33 and the openings 34 in the plate 32 to receive the screws 33 are elongated as shown in Figure 5 to permit adjustment of the plate as desired.

Secured to the plate 32, inwardly of one end thereof, by screws 35, is a hinge 36, which is screwed to the upper plate or blade holder 37 by screws 38. Secured to the plate 32, inwardly of the opposite end thereof, by screws 39, is the spring catch 40, which is so mounted that the hooked end 41 thereof will engage the holder 37 and retain it in closed position. The upper surface of the plate 32, intermediate the hinge 36 and catch 40 is slanted downwardly as at 42, Figure 3, while the lower surface of the holder 37 is complementary shaped as at 43, Figure 3. The surfaces are spaced apart to form the inclined groove 44 to receive the razor blade 45 whereby the blade is retained at the proper sharpening angle. Pins 46 in the plate 32 engage the conventional notches in the single edge blade 45 to retain the blade in position. The holder 37 is countersunk at 47 to receive the upper ends of the pins 46.

In use, when the sharpener is first used or even in subsequent use thereof, the plate 14 is removed so that suitable dressing may be applied to the material 29. After the plate 14 has been replaced, the base 12 of the casing 11, is placed on a convenient flat supporting surface. The holder 37 is disengaged from the catch 40 and moved up-

wardly by means of the hinge 36, so that the blade 45 can be positioned on the surface 42 of the plate 32. The notches in the blade engage the pins 46 in the plate 32. The holder 32 is then swung closed, and the catch 40 engaged therewith. If the angle of the blade 45 is not in proper relation to the material 29, the screws 33 may be loosened for the adjustment of the plate 32. After the plate 32 has been adjusted, and the screws 33 tightened, the sharpener is ready for use. By holding the casing 11 with one hand and rotating the crank 21 with the other hand, the material 29 will contact the blade 45 for the sharpening and honing thereof. The effect of the zig-zag movement of the material has the effect previously described.

A blade, by the proper sharpening and honing thereof may be used indefinitely, since there is little wear on the sharpened edge of the blade during the sharpening and honing process.

It is believed that from the foregoing description, the construction, operation and advantages of the sharpening and honing device will be apparent to those skilled in the art, and it is to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

A razor blade holding means for a sharpening mechanism having a casing, a rotary honing means mounted therein and a blade receiving opening in the top of the casing, comprising a

pair of L-shaped brackets secured to opposite sides of the casing, a blade supporting plate having elongated slots in its opposite ends secured to said brackets and the slots permitting adjustment of the plate with relation to the opening in the casing so that a blade placed on the plate can be adjusted with relation to the honing means, a clamping plate hinged at one end to said first plate adapted to engage and hold the blade on the first plate, and a spring catch carried by the first plate and engaging the second plate to retain the plates in fixed relation to each other.
